FLUID OPERATED CLOSURE SYSTEM

Claude W. Ritchie, Bealeton, Va.

Application June 1, 1939, Serial No. 276,922

8 Claims. (Cl. 268—58)

The invention relates to automatic doors and particularly operating means and door structure peculiarly novel and combined, and has for an object to provide a door which is adapted to ready operation with a minimum of structural elements and providing a maximum clearance for objects inwardly thereof as well as exteriorly.

An important object of the invention is to present such a door which may be operated automatically, from within and without the building closed thereby. Another important object is to present a novel means for securing the operating means against unauthorized operation.

Another important aim of the invention is to construct novel means to minimize air losses and enable the alternate operation of the door from either side. A still further object is to present a novel means for exhausting operating fluid from one side of the system when pressure is applied at the other for movement of the door.

It is a prime object of the invention to present a door and operating means which will be secured in closed position automatically so as to prevent casual or unauthorized movement of the door from closed toward open position except on operation of the opening means, and which is constructed in a novel form to operate automatically by manipulation of a simple control.

It is an advantage of my invention that all of the mechanical and door mounting parts may be encompassed within the building and so protected from the weather. Another attainment is the elimination of any obstructive framing or operating elements adjacent or so near the floor as to interfere with the common utilization of space within and adjacent door openings or elsewhere within the building.

Additional objects, advantages and features of invention reside in the construction, arrangement and combination of parts involved in the embodiment of the invention as will appear or be understood from the following description and accompanying drawings representing the embodiment of the invention in the best form thus far perfected, wherein

Figure 1 is a diagrammatic view of the system with the door in edge elevation.

Figure 2 is a vertical section of a door installation in a plane with the main operating cylinder and central carriage;

Figure 3 is a detail of the combined hanger and latch operating means and carriage;

Figure 4 is a top view of the central latch operating levers;

Figure 5 is an inner elevation of the door and

frame showing the latch bolts, cables and counterbalance;

Figure 6 is a detail section of one operating valve;

Figure 7 is a cross section thereof.

Figure 8 is a detail longitudinal section of the lock.

Figure 9 is an inner end view thereof.

Figure 10 is a cross section of the lock;

Figure 11 is a detail of an automatic switch valve.

Figure 12 is a similar view of an automatic exhaust valve.

Figure 13 is a fragmentary elevation similar to Figure 2, showing a modification of the door mounting.

There is illustrated a building structure 15 such as a garage, although the invention is adapted to use in various other situations and buildings, this illustrated structure having a door opening framed as at 16 in a conventional way. The building includes a ceiling 17 supported by usual joists 18, and a floor 19 is shown extending to the door opening and formed with an integral weather stop 20, the floor being continued outwardly thereof as an apron portion 21, corresponding to a sill. The door framing includes a lintel portion 22 and jambs 23, all of standard frame construction in the present instance, which may be modified without impairing the utility of my invention and without requiring any changes of construction in the invention.

Affixed to the jamb structure at each side of the door opening there is a vertical rectilinear channel track 25 of common form for guiding rollers, while normal to the plane of the closed door and located a distance thereabove in a vertical plane midway of the width of the door there is a horizontal double channel track 26 of familiar construction. At each side of the door opening there are respective supplementary curved single channel tracks 27 the lower ends of which are spaced slightly inwardly of the plane of the closed door and begin at a considerable distance above the floor, extending in vertical planes upward and inward, stopping a short distance inwardly of the door frame. The track 26 may be attached to the ceiling in cases where this is low enough, as shown, but conventional methods of support otherwise may be followed. The curved track may be attached to the jambs and ceiling, side walls, or other supports as required.

The door may be of a construction conforming to usual mill practice and architectural designs, and includes an upper section 29 which may

comprise the upper half or more of the door, supported at its upper edge upon a carriage 30 presently to be described, travelling in the track 26, while hinged to the lower edge of this door section, there is a lower section 31, adapted to extend to the surface of the apron 21, or close thereto, and to rest against the stop 20, when the door is closed. While only two sections are shown, it will appear that by proper location of the track 25, a multi-section bending door may be incorporated.

It will be seen that when closed, the entire door is suspended from the carriage 30.

At each side of the lower section a respective single roller 32 is mounted on a stud shaft or pintle suitably bushed in the edge of the door. The lower edge face of the door may be relieved sufficiently to pass closely between the jambs, while the door above is of a width to engage against the jambs and effect a good close joint.

Adjacent the hinge joint between the upper and lower sections of the door, attached to either the upper section or the lower section, and illustrated as attached to the lower section in the present instance, there are brackets 33, at respective sides of the door, each carrying a roller 34, engaged in the curved track 27 thereadjacent.

The carriage 30, consists of a central elongated body 35 having rollers 36 mounted on each side thereof at each end, and travelling in respective adjacent rail elements of the track 26. The bar is centrally recessed and has hung therein pivotally a hanger 37, midway between the two pairs of rollers, so as to swing freely in the vertical medial plane of the carriage. The hanger is of a peculiar form in the present instance, adapting it to clear the cables of a counterbalance to be described. For this reason it is formed with a substantially U-shaped part 38, the upper arm 39 of which is joined to a lateral part, the end of which is pivoted on the carriage, the lower arm 39 however is slightly shorter than the other, and when the door is closed and the carriage is at the forward or outer limit of its movement on the track 26, the long arm 39 extends forwardly a distance over the door, and then upwardly into the recess of the carriage body, where it is secured by a transverse pintle. The remainder of the hanger extends downwardly from the inner part of this arm 39, and thence forwardly to its point of attachment to a bracket 41 on the door and projecting slightly from the inner or rear face thereof. However, the weight of the door causes the hanger to swing down and draw the carriage slightly inward from its furthest possible forward position so that the hanger is suspended substantially as shown in Figure 3 where the axis of the pivot on the door is on a vertical line with the pivot of the hanger on the carriage. The hanger is formed with a strike or bill 42 projected downwardly from the lower side of the arm 40 distant from the pivot and from the door, and a horizontal, transverse latch-operating bar or tube 43, spring loaded, movable horizontally toward and away from the door and normally at a distant position from the door adjacent or against the bill 42. The bill has a curved face at the side next the bar 43 so that it may wipe against the tube and press it forwardly toward the door when the hanger is swung inwardly at the upper part (this causing the bill to move outwardly against the bar 43). The bar being tubular is supported on two inserted arms of horizontally movable bell crank levers 44 pivoted on suitable brackets on the inner side of the door. These

arms are inserted in the ends of the tube, having partly circular or spherical base parts 45 within the ends of the tube, and shoulders 46 adapted to abut the ends of the tube when the arms are on a common line between their pivots. The outer ends of the arms are conical from the partly circular or spherical parts, so that by striking the inner side of the tube, they limit swinging movement of the bar and bell cranks. Pivoted bolts 47 are provided at respective sides of the door, these being elongated triangular plates pivoted at one end on the door and each having a long arm projected laterally beyond the adjacent vertical edge of the door, as at 48, and engaged in a keeper 49 fixed on the door jamb, this keeper having a sloped upper side on which the arm 48 may ride as the door moves to closed position, and being the upper side of an upwardly projected bill portion 50 to receive and hold the arm 49 forwardly thereof when the door is closed. The plate 47 is extended upwardly at the upper side near the base and has connected thereto a cable or wire 51, which is extended inwardly before the door and attached to inwardly projected arms 52 of the bell cranks, so that when the parts 45 of the levers are pressed forwardly by the bill 42, the arms 48 are lifted from the keepers and the door freed for inward movement at its upper part. Springs 53 may be coengaged between anchorages on the door and the bolts, to hold the latter yieldingly engaged in the keepers, and guide and stop straps 54 are engaged over the long arms of the bolts to retain them in their plane of movement and stop them at proper limits of their swinging movements.

It may be understood from the foregoing that when the carriage is drawn inwardly it will cause the hanger 37 to swing in such manner as to release the bolts, unlatching the door, and that continued movement of the carriage will then draw the upper end of the door inwardly, and rearwardly. The lower part of the track 27 will oppose inward movement of the middle part of the door, and the rearward travel of the upper part will cause the lower portions of the door to rise upwardly in the tracks 27 and 25, and the middle portion will then move rearward on track 27 until the track 27 and the counterbalance lift the door to horizontal overhead position.

The counter-balance consists of cables 55 and 56, attached to the door, one at each side, at or adjacent the mountings of the rollers 32. From this connection the cables are both extended vertically upward and then one 56 carried laterally over one side of a double pulley 57 on the lintel and downwardly beside the door jamb, while the cable 55, is extended transversely over a pulley 58 and across the full width of the door to the pulley 57, around which it is passed downward in close relation to the cable 56. Both may be joined in one immediately beyond the pulley 57 while the door is in closed position. Just beyond the pulley 57 the cables are attached to a suitable weight 59 adapted to nearly counterbalance the door. Other locations of the weight and cable arrangements may be chosen in accordance with prior practices in such doors, as found desirable.

For operating the door, a main cylinder 60 is mounted horizontally just above the level of the track, and located just rearwardly of the innermost position of the carriage 30 when the door is raised. In this cylinder there is reciprocable a piston 61 from the forward end of which a long piston rod 62 is extended through the forward end of the cylinder with any usual packing and

connected suitably to the rear end of the carriage body. The rod and cylinder are slightly longer than the required horizontal movement of the upper part of the door inward from the closed position to full open position. This permits the carriage to move sufficiently forward of the plane of the closed door to insure its certain closing.

The piston 61 may be operated either hydraulically or pneumatically by suitable pressure liquid supply and return, but in the present instance to adapt it to the simplest requirements, it is adapted to the use of compressed air, which may be supplied from a compressor or other conventional means at 63.

Means is provided for transmitting air pressure to either end of the cylinder alternatively and manually or otherwise controlled at either of two or more points, one of which may be located exteriorly of the building and the other at a distance from the first either inside the building or elsewhere. These controls may be variously operated, but for simplicity are here shown as manually operated, and but two are illustrated.

The controls are dual valves 64—64', each consisting of a casting in which a pair of parallel cylinders 65 are formed and smoothly finished, opening in a common direction on the outer side of the unit. Around the inner ends of the cylinders a reservoir chamber 66 is formed, communicating with which there is a pipe 67 leading from the supply 63. The cylinders are ported concentrically at their inner ends in communication with the chamber 66, formed with seats 68 next the chamber and closed by poppet valves 69 seated over the ports within the chamber. These valves each consist of a metal disc 70 centrally apertured and receiving a threaded tenon of an operating stem 71 projected from the valve through the port, the disc having a seat facing 72 of rubber or other material adapted to assure a sealing fit against the seat. Screwed on the tenon at the inner side of the valve there is a tubular stem 73, receiving slidably a stud pin 74 fixed on a plug 75 screwed into an opening in the wall of the chamber in registry with the respective cylinder, the stud pin serving as a guide for the valve, and so being short enough to permit required opening movement of the valve. A helical spring 76 is confined between the valve and the plug 75, to normally seat the valve.

The two cylinders are spaced comparatively close together, and mounted pivotally on the casting 64 between the cylinders, there is a rocking lever 77, its ends adapted to move longitudinally of the axis of respective cylinders, the lever having a handle 78 projected outwardly therefrom at right angles so as to depress the stems of the valves alternately. For the purpose of sealing the outer ends of the cylinders, each one has mounted therein a piston or dasher 79, connected to a respective arm of the lever 77 by a link 80 pivotally connected to the lever and dasher. A lateral port 81 is formed in each cylinder intermediately of its length. If desired, a seat 82 may be formed within the cylinder outwardly of the pipe connection 81 on which the inner end of the dasher 79 may engage, the latter faced suitably to effect a good seal when the dasher is pressed against the seat. The stems 71 are of a length to lie close to the respective ends of the lever 77 when the valves are closed, and to be engaged by a respective dasher when the handle 78 is rocked in that direction, so that the valve is thereby pressed from its seat, admitting compressed air from the reservoir

66 to the cylinder 65, from which it may pass to one end of the main cylinder 60.

The valves 64 and 64' are customarily mounted with one of the cylinders above the other on horizontal axes, and to make the effect of their operation readily understood and remembered, the upper cylinder of each valve is utilized to effect opening of the door, by raising of the handle 78. Correspondingly, downward pressure of the handle causes closing of the door. For communicating the pressures properly to the main cylinder, pipes 82' are led respectively from the ports 81 of the upper cylinders of the two valves to opposite ends of a junction valve device 84, from the middle of which a pipe 85 is led into the front end of the cylinder 60. Also, pipes 86 and 87 are respectively led from the lower cylinder of each valve to a junction valve 88, from the middle of which a pipe 89 is led into the rear end of the main cylinder, as in Figure 1. An automatic exhaust valve device 90 hereinafter described may be connected between the pipes 85 and 89, and consequently between the opposite ends of the cylinder 60, by pipes 91, leading into respective ends of the valve 90. However, the valves 64—64' are adapted to function as exhaust valves by the formation of a longitudinal groove 65' in each cylinder opening on the outer end of the cylinder and stopping just short of the plane of the seat 82.

The valves 84 and 88 are identical and each consists of a cylinder 92 having inlet ports 93 at each end to which the pipes from the valves 64 and 64' are connected, and a central lateral port 94 opening through the wall of the cylinder, with which port the pipe 85 or 89 is connected, as the case may be. Freely slideable in the cylinder there is a dasher 95, having an annular seat rib 96 on each end, while fitted in each end of the cylinder there is a seat washer 97 against which the respective end of the dasher may seat to close communication between the adjacent port 93 and the port 94. In consequence, when air enters one end of the cylinder 92 from one of the valves 64 or 64', the dasher is forced to the opposite end of the cylinder, closing communication between the open hand valve and the one not operated, avoiding leakage and waste of air in filling unused passages.

The exhaust valve 90 consists of a cylinder 98 in two parts joined by being threaded into a central sleeve coupling 99. Held between the ends of the cylinder parts there is a spring seat washer 100 apertured to form free communication between the opposite ends of the cylinder 98, and affording seats for respective helical springs 101, which are confined against the seat washer by respective dasher pistons 102 slideable in the cylinder. These are intended to hold between them a loading of oil 103, the pistons being shown as double cup-washer elements of conventional construction. While it may not be essential, they are shown as having set between them a tube 104 by which they are spaced apart, and they are held pressed against the ends of the tube by means of nuts 105 screwed on respective ends of a dasher or plunger rod 106 engaged through both pistons and projecting beyond each one toward the adjacent end of the cylinder. Each end of the cylinder is exteriorly threaded and has engaged thereon a valve case 107 corresponding to a pipe L. The outer end is bushed as at 108 to afford a small pipe coupling suitable for the air lines to and from the main cylinder represented by the pipe 91, which are engaged therein.

Opposite the bushing a ported seat 109 is formed, this being the lower side of the device as installed. On this seat there is shown a valve 110, pivoted on a transverse pin 111 engaged through the wall of the fitting in a familiar way. The valve is formed with an upwardly extending operating arm 112 which projects across the axis of the rod 106, with a clearance behind the arm next the wall of the case to permit it to swing and open the valve. The rod 106 is of a length to stop short of, but close to, the arms 112 of the valves, so that a little movement of the rod in either direction will open one valve. The springs 101 are so adjusted as to tend to hold the plunger rod in a central position clear of both valves.

It will be appreciated that upon admission of air pressure to either end of the main cylinder 60, the dasher unit and plunger of the valve 90 will be moved from that end of the cylinder 98 which communicates with such end of the main cylinder, so as to open the valve 110 at the opposite end, and that opens communication between the end of the main cylinder from which air must be vented to avoid back pressure opposing operation of the door as required. The oil 103 may be replenished through an opening in the coupling 99, this opening being closed by a plug 113.

In the case of a valve 64 located exteriorly of a building or room, the door of which is controlled thereby, I have provided a lock device 115, as shown in Figures 7 to 10 inclusive. This is incorporated as a part of the valve, and is constructed and adapted to lock communication through the pipe 82 by which pressure for opening the door is communicated from this valve. In the present instance, the lock consists of a lock case similar to those used in Yale locks but slightly elongated at the inner end. The forward part may conform to standard Yale lock construction, and includes the case portion 116, with the usual conformation, flange and threads for mounting, the coaxial rotating barrel 117 with the key slot 118, plunger-and-tumbler set 119 of ordinary form and function. In addition, however, the case is formed with a complementary set of plungers 120 located on a radius at an angle of ninety degrees to the radius of the normal set, the latter being shown at the top of the case.

The rearwardly extended portion of the case is tubular, forming a chamber 121, of larger diameter than the barrel 117 and having opposite ports 122 adapted to receive respective sections of the pipe 82. The inner end of the case and chamber is closed by a simple socket plug 123. On the inner end of the barrel 117 which is projected slightly within the chamber, there is secured a spring plate 124, the base end of which is flat and secured against the end of the barrel by screws, the other end constituting a spring arm extended at right angles to the base end and tending to lie against or close to the annular wall of the chamber. This arm has on its outer face a button valve 125, which may be faced with a compression washer 126, if desired. For sealing the joint around the barrel, I have set in the outer end of the chamber against the body of the case and around the barrel a washer 127 of rubber or other suitable material, and secured against the end of the barrel, held under the plate 124 there is a spring cup washer 128, the edges of which press against the washer 127, forming a seal throughout movement of the barrel. With the lock element in locked position

as shown, with the tumblers locked in a vertical plane, the valve 125 will close the lower port of the chamber 121, and by leading the pipe 82 from this lower port to the main cylinder 60, passage 5 of fluid to the cylinder is readily prevented with a minimum of strain of, or leakage at, the valve.

If it is desired to withdraw the key (not shown) of the device, while the valve is in open position, the key is turned to register the tumblers in the 10 barrel with the extra set of plungers 120, whereby the key may be withdrawn, the valve being thereby locked in open position.

While I have shown the invention embodied in a particular specific form, I do not regard it as 15 limited thereto, and various modifications of structure and arrangement may be made without departing from the spirit of the invention as set forth in the appended claims.

Thus, in Figure 13 I have indicated an alternative 20 to the use of the curved track 26, which consists of mounting a suitable pivot block 130 at each side of the doorway and spaced inwardly thereof a distance, and upon this pivoting a bar 131, attached to the door adjacent to the hinge 25 connection between the upper and lower sections, or otherwise. This bar will cause the lower part of the door to move approximately in the same path as the roller 32 and track 26. The block may be mounted on a wall, or pier, or any 30 other building element either specially provided, or involved in the plan for structural elements of the building.

A vertical secondary cylinder 132 is mounted 35 at the upper end of the vertical track 25 at each side of the door, and in this there is reciprocable a piston 133 having a rod 134 projected downwardly from the cylinder and longitudinally within the track 25, and in the path of the roller 32. A strike 135 is secured on the edge of the door, having an outturned flange 136 over the roller 32 to engage the lower end of the piston rod. The latter is fitted with a cushion bumper head 137 having the cushion material at both 40 upper and lower sides for reasons to be explained. The material at the lower side will quiet the engagement of the piston with the strike when the piston rod is projected downwardly with the piston, and the cushion material at the upper side of the bumper head will cushion 45 the stoppage of the upward movement of the piston rod by the door when the bottom of the latter arrives at the upper limit of its movement. This last movement is stopped by a stop plate 138 mounted in the track and being projected 50 on each side of the rod 134 so as to receive the bumper thereagainst as the latter moves upward.

A pressure supply and vent pipe 139 is in permanent open communication with the upper end 60 of the cylinder 132, and the rear end of the main cylinder, so that whenever pressure is admitted to the rear part of the main cylinder tending to move the door forwardly, such pressure is also communicated to the secondary cylinder, 65 causing the piston 133 to move downwardly, the bumper head 137 pressing the striker 135 downward and moving the outer part of the door downwardly. The cylinder 132 is only of such length as to move the bottom edge of the door downward a short distance, after which the action of the main piston 61 will by forward pressure on the upper part of the door cause the bottom edge to continue its downward movement, and the rollers 34 in the curved track or 70 the connection with the arm 131 will cause proper 75

downward movement of the intermediate portion of the door.

In the movement of the door to open position, the upward movement of the strike against the head 131 will cause compression of air in the cylinder 132 to a limited extent, its escape through the pipe 139 being sufficiently retarded to cause the secondary cylinder and its piston to function as a check, so that the door will not move with excessive speed into engagement with the stop 138.

A helical spring 140 is located in the lower end of the cylinder 132, to cushion stoppage of the piston when it reaches the lower limit of its movement in the cylinder.

In the use of the apparatus, to open the door, one of the handles of the valves 64 and 64' is raised manually. This movement is at first opposed by the pressure against the valve in the upper cylinder, but as soon as the valve has been opened, this resistance quickly diminishes, so that the pressure exerted by the person operating the handle causes it to be moved abruptly to its full stroke, bring the respective piston 79 against the seat 82, and so closing off the groove 65' and preventing waste of air. The air displaced from the main cylinder as the piston 61 moves rearwardly is vented through the groove 65' of the lower cylinder of the control valve which has been operated, and also this is vented through the grooves 65' of the other control, the pistons therein being held at their normal positions spaced from the seats 82, and uncovering the ends of the grooves 65'. In closing of the door the air from the front end of the main cylinder is correspondingly vented.

It should be appreciated that an important advantage of my invention lies in the fact that fluid pressure is not depended on to support or retain the door in either open or closed position, and when it is in either of these positions normally the fluid supply is entirely cut off, and not subject to leakage or waste past pistons. Also, the fluid pressure is utilized only to move the door from either limit of its movement, and the door may be partly opened and will remain at any intermediate position until it is desired to move it further or to return it to its initial position, without utilizing the fluid pressure device.

It is apparent that the track 26, carriage 30 and cylinder 60 connected with the door may be duplicated where the width of the door requires it. This is a further important advantage of the invention, as it enables its use to support and operate doors of any width. In such duplication mounting, it is not necessary to multiply the secondary cylinders 132, two being adequate for a very wide door, and conventional stays may be incorporated on the door to stiffen and hold it in planiform shape. The connections between the counter weight and door may also be multiplied as found desirable, and the weight may be in two or more parts, if desired in accordance with conventional counter-balancing practices. This is of great value in hangers, where doors of 100 feet width are common.

It should be appreciated that my lock device is so coordinated with the system that when the lock is locked with the door in open position, it will not prevent closing of the door by use of either of the hand valves. In such case, the air returning from the main cylinder and requiring to be exhausted through the port groove 65' of the cylinder the outlet from which is closed by the lock will lift the valve 125, the spring arm

124 permitting this, so that the lock valve will function as a check valve, permitting return flow but positively closed against out-flow that might open the door. Also, by the arrangement shown, the lock being located in the exterior valve 64, it will not prevent opening of the door by operation of the interior valve 64'.

It is an important advantage of my invention that in case of failure of the compressed fluid or liquid supply, the door may be operated by hand from within the building by the use of any familiar hand cable connection 131 to the upper part of the hanger 37 or latch bolts 41, and with the construction otherwise as the same as illustrated, but the door can not be operated from without.

The groove 65' in one cylinder is uncovered by the piston 79 therein when the piston 79 at the opposite side of the particular control valve 20 is engaged against the seat 82, and this provides for exhaust of air freely from before the advancing piston in the main cylinder 60. The grooves 65' are uncovered at normal released position 25 of the handle in each of the valves 64 and 64', so that exhaust may occur through either of the valves 64 and 64', according to the position of the junction valve through which the exhaust passes.

With the use of this construction, the automatic exhaust valve 90 is not absolutely essential and may be omitted, but may be provided as a safety feature if desired, or to shorten the path of air to the point of exhaust. For emergency closing of the door, as in case of fire in a garage 30 equipped with my door system, a supplementary pipe line 152 may be connected between the pressure supply 63 and the proper operating end of the cylinder 60, normally closed by a fuse plug 153 which will melt at a predetermined high temperature, admitting fluid under pressure to the cylinder from the supply 63. The connection of the pipe 152 is made to the pipe 89, and a junction valve 154 similar to that of Figure 11 may be included there to direct the pressure fluid only 35 to the cylinder 60.

It should be appreciated also that while I have illustrated a sectional door because of the greater clearance thereadjacent in its opening movement, my invention may also be applied to a one-piece door, eliminating the curved track 27 and midway rollers 34 and the side track and side roller connections may be connected with such a door in accordance with prior practice in the pivoting of overhead one-piece doors at the sides, which 40 is to say, the side rollers may be higher on the door than illustrated. My overhead track and carriage and latch constructions may be the same as already described for such a door, whether a single set or a multiplicity are used.

My invention is adaptable to use with doors of metal or of wood, or both, as well as doors of other materials, and where transverse reinforcement is required, it is an advantage of my invention that on ordinary private garage doors this may take the form of angle iron secured with one flange over the top edge of the door and one flange against the inner side of the door, and it is not necessary to apply such angle iron stiffening at a midway position on such doors, where 45 it will project considerably inward from the face of the door.

It will be appreciated also, that the valve 64 located anywhere that is convenient is readily adapted to be operated electrically by any conventional construction suitable for such use, so

that automatic distant control action may be attained in response to various requirements, such as automobile wheel movement, car movement, light interception, etc., various apparatus for which are known, adaptable to the uses indicated.

An important advantage of the invention presented lies in the ease with which the manual controls may be operated, yet avoiding risk of accidental operating of the valve, because of the initially higher pressure required to be overcome before the valve opens.

It is another important advantage of my invention that by reason of the dash-pot function of the secondary cylinder or cylinders, need for large compensating springs to prevent slamming of the door on either opening or closing movement is obviated. These springs are required on most of the overhead door mountings now used.

I claim:

1. A closure of the character described consisting of a closure body having a normal vertical closed position and movable at one part in a substantially horizontal direction to an open position, means to support and guide the opposite portions of the body for movement thereof toward the initial position and path of the first named part, means to move the said one part comprising a draft and including a carriage member movable generally in the direction of movement of said one part of the closure, and located initially a distance laterally from the body, a lever pivoted thereon projected before the body and pivoted on an axis fixed with and spaced from the body, said lever having an operating bill projected beyond the last named pivot, spring loaded bolt means to secure the door in closed position, means to draw the bolts including a member movable in line with said bill and normally positioned near the bill and movable in a direction for operation by said bill to draw the bolts.

2. The structure of claim 1 in which said means to move one part comprises a main operating cylinder, a piston therein connected to the carriage, means to supply pressure fluid alternately to the opposite ends of the cylinder, a secondary operating cylinder mounted parallel to the closed position of the closure body and near the initial position of the first named part thereof, a piston in the secondary cylinder and projected from the cylinder in the direction of closing movement of the closure body, said body having a strike projection on its distant part positioned to engage the piston in the terminal portion of opening movement of the strike, and to sustain pressure of the piston thereagainst a distance in initial closing movement, and an open duct connected between one end of the main cylinder and the secondary cylinder for projection of the last named piston simultaneously with initial closing movement of the piston of the main cylinder.

3. A door and the like and opening system of the character described consisting of a door frame, a vertical guide device at each side thereof, a horizontal guide track thereabove and extending generally inward from adjacent the frame, a support member on the track engaged with the upper edge of the door, a third guide device constructed to guide an intermediate portion of the door in a curved path from closed position to full open position, means connecting the last named guide means and intermediate portion of the door, a main operating cylinder,

a piston therein, operative connections between the piston and the upper part of the door for movement of the door upon said horizontal track, fluid pressure means to operate the piston, a vertical cylinder adjacent the upper part of said vertical guide, an open duct between the upper end of the last named cylinder and one end of the main cylinder, a piston in the vertical cylinder having a rod projected downwardly from the cylinder, and a strike member on the portion of the door guided by said vertical guide arranged to engage the rod.

4. The structure of claim 3 in which a cushion stop is interposed in the path of movement of the piston.

5. The structure of claim 3 in which a stop is positioned in the path of movement of said strike to limit opening movement of the door.

6. A closure of the character described consisting of a body having a normal closed position and having an edge portion movably mounted for movement with a major horizontal component of direction, and an opposite portion mounted for movement with a major component of direction at right angles to the first named component, to a predetermined open position substantially at right angles to said closed position, a main operating cylinder substantially coincident with the first named direction, a piston therein, operative connections between the piston and said first named edge portion of the closure, a secondary cylinder substantially coincident with the second named component of direction, a piston therein, an open duct connection between one end of the last named cylinder and one end of the first named cylinder, and means to supply pressure fluid to each end of the first named cylinder alternatively.

7. The structure of claim 6, in which said open duct connection is constructed to restrict flow from the second named cylinder sufficiently to retard opening movement of the second named edge portion of the door as a dash pot.

8. A closure of the character described consisting of a closure body having a normal closed position plane and movable at one part from said plane in a direction having a substantial component vertical to said plane, means to support and guide the said one part in said movement, a main operating cylinder substantially coincident axially with said direction and having a piston therein connected to said one part, means to supply pressure fluid alternately to opposite ends of the cylinder, means to support and guide a distant portion of the body for movement toward the initial position and path of said one part, a secondary operating cylinder mounted parallel to said plane near the terminal open position of said distant portion of said body, a piston in the secondary cylinder having a part projected from the cylinder in the direction of initial closing movement of said distant portion, a strike element on said distant portion positioned to engage the last named piston in the terminal opening movement of said distant portion and to sustain pressure of the piston thereagainst a distance in initial closing movement thereof, and a duct connection between at least one end of the main cylinder and the secondary cylinder for projection of the last named piston simultaneously with initial closing movement of the piston in the main cylinder.
